UNITED STATES PATENT OFFICE

2,125,209

DOORWAY STRUCTURE FOR BOXCARS

William L. Thomas, Haverstraw, N. Y., assignor to
The New York Central Railroad Company, a
corporation of New York

Application August 9, 1937, Serial No. 158,218

10 Claims. (Cl. 105—376)

This invention relates to improvements in boxcars, and particularly to means for holding partitioning or supporting elements for partitioning the car into holding compartments, and/or providing therein supporting floors or platforms of suitable size or sizes for holding or supporting different kinds or sizes of goods to be shipped.

More particularly the invention relates to means for supporting the supporting or holding elements in the car between the door ways of the car, in such manner that such supporting and holding elements may be positioned to lie in the same longitudinal plane throughout the length of the car.

15 The general object of my invention is to provide improvements in the means shown in my Patent Nos. 2,016,731, October 8, 1935, 2,038,692, April 28, 1936, and 2,030,773, February 11, 1936, for variably partitioning the interior of a box car 20 to divide the same into holding compartments and/or to support therein floors or platforms whereby one and the same car may be used to hold mixed kinds and/or sizes of goods in separate lots and in such manner as to keep the 25 lots separated from each other, and to prevent shifting of the goods in transit and to enable the full capacity of the car to be used for shipment of such goods to same destination or to different destinations.

30 The particular object of the invention is to provide partitioning and supporting means across the doorways and across the interior of the car between the doorways for the purposes above described, and which are of such construction as 35 to furnish a more convenient and flexible arrangement for changing the supporting and partitioning elements as may be required under different conditions of service, and to provide the supporting elements which span the doorways 40 with perforations similar to the perforations in the lining of the car, so that the inner face of the door spanning member is flush with the face of the lining whereby I obtain continuous rows of perforations, from end to end of the car, all 45 rows of perforations in the door spanning member lining up with the perforations in the lining sheets of the car.

The invention consists of the features of construction, combination and arrangement of parts 50 hereinafter fully described and claimed, reference being had to the accompanying drawings in which:

Figure 1 is a detail horizontal sectional view through a car doorway and immediately associated parts.

Figure 2 is a vertical horizontal section of a portion of a car embodying my invention.

Figure 3 is a rear elevation of my improved doorway spanning bar.

Figure 4 is an elevation of one end of the door bar from which the fixed supports extend.

Figure 5 is a detail vertical sectional view through the doorway of a car showing the vertical row of perforations in one of the door stiles.

Figure 6 is a top plan view of the door bar. 10

Figure 7 is an end elevation of the door bar carrying the sliding bolts.

The reference numeral 1 designates the car body which is or may be of usual box body form, and comprises the bottom 2, side walls 3, end 15 walls 4, and roof 5. The bottom 2, end walls 4 and roof 5 may be of any suitable and approved construction. The side walls 3, however, may be of special construction, as disclosed in my Patent No. 2,030,773, to adapt the same for use 20 in conjunction with supporting and/or partitioning members, whereby the interior of the car, between the end walls and the doorways 6 may be divided into goods holding compartments, and/or provided with shelves or platforms for 25 supporting goods of different sizes or kinds therein.

Each side wall 3 is provided with a doorway 6 including door posts 7, which posts are provided with a vertical row of perforations 8 located adjacent to the inner corners of the posts facing the doorway.

The side walls of the car are faced inside of the car with strips or sheets 9 covering substantially the entire area of the side walls from top 35 to bottom, and are provided with horizontal and vertical rows of perforations 10 (preferably elongated, the edges of the sheets being suitably secured to the door posts 7. The ends of the supports 11 are suitably secured in the perforations 40 10 of the lining sheets to support the shelves 12, as fully described in my Patent Nos. 2,030,773 and 2,038,692.

From experience in loading and operating these 45 cars I have found that it is desirable to provide the doorway spanning bar 13 with horizontal and vertical rows of perforations corresponding with the perforations in the side wall lining, and to so position said bar in the doorway that its front 50 face is flush with the vertical plane of the perforated lining of the car side walls to ensure that a series of these bars may be set up in the doorway to obtain continuous rows of perforations 14, from end to end of the car; all rows of per- 55

forations in the bars lining up with the rows of perforations in the car side linings.

The door bar 13 is shown as a channel shape in one end of which, and in the channel thereof, is suitably secured an angle 15 to one arm of which are fixed locking members or studs 16 which are adapted to be seated in the vertical row of perforations 8 of the door posts 7. To the other end of the door bar 13, and in the channel thereof, I suitably secure a casting 19 having bolt slideways (two being shown) in which suitable bolts 20 are slidably mounted, said bolts having an operating handle or knob 21, whereby the bolts may be operated to locked and unlocked position. A slideway 22 is provided in which said handle may be moved, the ends of the slideway being at right angles to the straight-away portion of the slideway in which the handle may be positioned to lock the bolt in locked or unlocked position. These bolts are designed to engage and become locked in the vertical two of perforations 8 in the opposite post.

The angle 15 and casting 19 are of proportions relative to the depth of the channel of the door bar 13 to offset the studs 16 and bolts 20 rearwardly of the body of the bar so as to position the face of the bar 13 flush with the face of the car side wall perforated sheets when the studs 16 and bolts 20 are in the vertical row of perforations on the door posts, so that a series of these bars 13 can be set up in the doorway to obtain continuous rows of perforations from end to end of the car; all rows of perforations in the bars 13 lining up with the rows of perforations 35 in the car side wall lining sheets.

What I claim is:

1. In a boxtype freight car, the combination of a car body having oppositely disposed walls, vertical sections spaced from the outer walls and 40 extending substantially from floor to roof, the said vertical sections being provided with vertical and horizontal rows of elongated openings, a plurality of supports adapted to be extended between and mounted upon said vertical sections 45 for supporting therefrom load carrying shelves and load carrying partitions, said supports having engaging elements interchangeably engageable with said openings to mount the supports in different horizontal and vertical spaced relationship to each other on said sections, door ways for said car, posts at opposite sides of said door ways and each having a vertical row of perforations therein extending substantially from floor to roof and supporting members designed to span each 50 doorway and each having locking projections at one end for engagement with the perforations in one of the posts and having a movable locking projection at its opposite end for engagement with the perforations in the other perforated post, said supporting members having horizontal 55 rows of elongated perforations so arranged, when the said member is in operative position, as to align with the perforations in the vertical section of the car whereby continuous rows of said perforations extend from end to end of the car.

2. In supporting and partitioning means for use in a boxcar, lined with sheets having elongated openings, doorways in said car provided with posts, said sheets being flush with the inner face of said posts, each of said posts having a vertical row of perforations therein, supporting members adapted to bridge between the posts of each doorway and having rows of elongated perforations designed to support partitioning or supporting members to be extended across the in-

terior of the car between the doorways, fixed locking projections extending from one end of each first-named supporting member and designed for engagement with the perforations in one of said door posts, and slideable locking projection at the opposite end of each first-named supporting member designed to engage the perforations in the opposite perforated post, said locking members being so mounted on said supporting members that when the supporting members are in locked position the inner faces of said supporting members will be flush with the faces of said lining sheets and the perforations of the supporting members will line up with the perforations in the lining sheets to obtain continuous rows of perforations from end to end of the car in the same plane.

3. The combination with a car of the character described lined with sheets having vertical and horizontal rows of elongated perforations, doorways for the car, the door posts of which have a vertical row of perforations, supporting members having rows of elongated perforations designed to support partitioning or supporting members to be extended across the interior of the car between the doorways, locking means on said first named supporting members designed to interlock with the perforations in said door posts so positioned on said supporting members that when in locked position the inner face of said first named supporting members will be flush with the faces of said lining sheets and the perforations of said first named supporting members will line up with the perforations of said lining sheets to obtain continuous rows of perforations in the same vertical plane from end to end of the car.

4. In a side wall structure for railway boxcars, channeled posts arranged to define a doorway, each post having a wall facing the interior of the car and a wall facing the doorway, the latter-named wall having a vertical row of perforations therein adjacent to the inside corner thereof facing the doorway, perforated supporting members mounted on the side wall at each side of the doorway in the same vertical longitudinal plane, and supporting members bridging the space between said door posts and having projections at the ends thereof engaging selected perforations in the posts and received in the channels of said posts, said supporting members at said doorway terminating at said inside corners of the posts and said projections and perforations being relatively arranged to dispose said doorway members in the same longitudinal plane with the supporting members at opposite sides of the doorway.

5. In a railway boxcar, longitudinally spaced posts affixed at each side of the car from end to end thereof including channeled door posts arranged to define a doorway, each door post having a wall facing the interior of the car and a wall facing the doorway, the latter-named wall having a vertical row of perforations therein adjacent to the inside corner thereof facing the doorway, perforated supporting members bridging the posts at each side of the doorway and disposed in the same vertical longitudinal plane, perforated supporting members bridging the space between said door posts and having projections at the ends thereof engaging selected perforations in the door posts and received in the channels thereof, said supporting members at said doorway terminating at said inside corners of the posts and said projections and perforations in the door posts being relatively arranged to dispose said doorway members in the same vertical

longitudinal plane with the supporting members at opposite sides of the doorway, and adjustable cross bars extending transversely of the car and having projections at the ends thereof engaging selected perforations of said supporting members.

6. In a side wall structure for railway boxcars, posts arranged to define a doorway, said posts each having a vertical row of perforations adjacent to the inside corner thereof facing the doorway, perforated supporting members mounted on the side wall at each side of the doorway in the same longitudinal plane, and supporting members bridging the space between said door posts and each having a set of spaced projections at each end thereof engaging selected perforations in the posts, at least one of said sets of projections comprising movable locking members, said supporting members at said doorway terminating at said inside corners of the posts and said projections and perforations being relatively arranged to dispose said doorway members in the same longitudinal plane with the supporting members at opposite sides of the doorway.

7. In a railway boxcar, longitudinally spaced posts affixed at each side of the car from end to end thereof including door posts arranged to define a doorway, said doorposts each having a vertical row of perforations adjacent to the inside corner thereof facing the doorway, perforated supporting members bridging the posts at each side of the doorway and disposed in the same vertical longitudinal plane, supporting members bridging the space between said door posts and having projections at the ends thereof engaging selected perforations in the door posts, each of said supporting members being provided with a longitudinal row of perforations, said supporting members at said doorway terminating at said inside corners of the posts and said projections and perforations being relatively arranged to dispose said doorway members in the same longitudinal plane with the supporting members on opposite sides of the doorway and said rows of members in longitudinal alignment.

8. In a railway boxcar, posts affixed at each side of the car from end to end thereof including door posts arranged to define a doorway, said door posts each having a vertical row of perfora-

tions adjacent to the inside corner thereof facing the doorway, perforated supporting members bridging the posts at each side of the doorway and disposed in the same vertical longitudinal plane, and perforated supporting members bridging the space between said door posts and having projections at the ends thereof engaging selected perforations in the posts, said supporting members at said doorway terminating at said inside corners of the door posts and said projections and perforations in the door posts being relatively arranged to dispose said doorway members in the same vertical longitudinal plane with the supporting members at opposite sides of the doorway.

9. In a railway boxcar, longitudinally spaced posts affixed at each side of the car from end to end thereof including door posts arranged to define a doorway, said door posts each having a vertical row of perforations adjacent to the inside corner thereof facing the doorway, perforated supporting members bridging the posts at each side of the doorway in the same vertical longitudinal plane, and supporting members bridging the space between said door posts and having projections at the ends thereof engaging selected perforations in the posts, each of said supporting members being provided with a longitudinal row of perforations, said supporting members at said doorway terminating at said inside corners of the door posts and said projections and perforations in the door posts being relatively arranged to dispose said doorway members in the same vertical longitudinal plane with the supporting members on opposite sides of the doorway and said rows of perforations in said members in longitudinal alignment.

10. In a railway boxcar, longitudinally spaced posts affixed at each side of the car including perforated door posts each having a vertical row of perforations disposed adjacent to the inside corner thereof at the door opening, perforated supporting sheets bridging adjacent posts at each side of the car, the supporting sheets at said door opening terminating at said inside corners of the door posts and being disposed in the same vertical longitudinal plane with the other supporting sheets, and adjustable cross bars disposed transversely of the car and having projections at the ends thereof engaging selected perforations of said supporting sheets at opposite sides of the car.

WILLIAM L. THOMAS.
